FREQUENCY MULTIPLICATION

Application filed December 2, 1930, Serial No. 499,450, and in Germany December 2, 1929.

It is known in the prior art that electric valves may be used not only for rectification of the current, but also for frequency multiplication. The circuit schemes adapted to this end are generally known and need not be enlarged upon here. Fundamentally, they are based upon the fact that the wave of the valve current, apart from the direct current component and the fundamental wave of the alternating current, contains a number of harmonics, which, by the aid of suitable coupling means and suitably tuned circuits, may be fed to the load or consumer apparatus.

The present invention has for an object 15 the provision of methods and means for amplifying these overtones or higher harmonics and/or to increase their number.

If the filament of a valve which works as a rectifier feeding thermionic tubes is fed 20 with alternating current, owing to this filament or heating current there arises in the valve, for instance, when the filament is grounded centrally, an additional superposed current of double frequency which proves 25 troublesome in the thermionic tubes as it appears in the form of a beat note of double frequency. Many attempts have been made to obviate this modulative action of the filament heating alternating current in the rectifier as far as feasible.

Now, according to this invention, quite distinct from the foregoing schemes, the modulating action of the alternating current heating the filament is utilized in the operation of 35 electric valves when working as low or high frequency converters, by choosing the frequency of the heating or filament current so that in relation to the fundamental wave a practical improvement of the desired frequency multiplication is attained.

Assuming that a valve is fed with an alternating current having a frequency $n_1 = 10,000$, and that its filament be heated with an alternating current whose frequency n_2 is also 45 equal to 10,000 cycles; then the fundamental wave of the valve current is modulated by the filament current at frequency n_m being twice the frequency of the filament current, in other words, 20,000 cycles per second in 50 the present case. As a result of such modu-

lation, there is produced in the valve current, apart from its fundamental wave of $n_1 = 10,000$, an additional side wave having a frequency $n_s = n_1 + n_m = 30,000$, while the other side wave having frequency $n_1 - n_m$ coincides 55 in this instance with the fundamental frequency.

As will thus be seen, the third overtone is produced or markedly increased by the influence of the filament frequency, a fact that 60 may be advantageous, e. g., for frequency tripling.

Using for heating the frequency $n_2 = 5,000$ then the influence of the heating by virtue of a modulating frequency of $n_m = 10,000$ manifests itself in this way that outside the fundamental wave of $n_1 = 10,000$ there is obtained a side wave of $n_s = 20,000$ and another side wave having a frequency $n_s'' = \text{zero}$, in other words, an additional direct current component. In a similar manner other frequencies could be chosen for the heating in order 70 to secure the desired amplification of a certain selected or preferential overtone.

In order that the amplitudes of the harmonics thus produced may be made as large as possible, it is advisable to so manufacture the filament that it will require as high a filament potential as possible, and to use, moreover, valves presenting a characteristic of 75 maximum slope for example, the well known mercury-vapor tubes furnished with a heated filament.

The invention is more fully described in connection with the accompanying drawing 85 wherein;

Figure 1 illustrates a frequency multiplier wherein currents of like frequency apply to the input circuit and to the cathode heating circuit, and

Figure 2 illustrates a similar system wherein currents of different frequency are applied to the input and filament heating circuits of a vacuum tube frequency multiplier.

Turning to Figure 1, alternating energy 95 from an oscillator 2 of suitable construction is applied to the input circuit of electron discharge device 4, through the action of transformer 6 and to the cathode heating circuit thereof through the action of transformer 8. 100

6 The frequency of currents applied, it is to be clearly understood, may either be a low frequency, such as an audio frequency, a superaudible frequency, or a radio frequency, depending upon the desired output. In the 10 output circuit 8 of electron discharge device 4, there will appear, in accordance with what has been said hereinbefore, a component equal to the third harmonic of the frequency of oscillator 2, which harmonic may be accentuated by suitably tuning output circuit 10 as indicated.

15 The output of frequency multiplier 4 may be fed to any suitable utilization circuit, or fed in a similar fashion to a similarly connected frequency multiplier for still further increasing the frequency of alternating current originally derived from oscillator 2.

20 In Figure 2, energy from a master oscillator 2 of any desired construction, is fed to a frequency multiplier 12 which may be, if desired, of the type shown in Figure 1. The output of frequency multiplier 12 is fed to the input side of electron discharge device frequency multiplier 14; whereas, energy of a 25 frequency of the same order corresponding to that of oscillator 2 is fed to the cathode circuit thereof through transformer 16 as shown. By suitably tuning the output circuit 18, energy of desired frequencies, as indicated, may be derived for direct use or for further frequency multiplication and amplification.

30 It is to be clearly understood, that the supply to electron emission tube 14 may be reversed if desired, the relatively low frequency being applied to the input electrodes through the action of transformer 18, and, the relatively high frequency energy being applied to the filament. Moreover, if desired, 35 the filament or cathode may be of the indirectly heated type although it is preferred that the cathode consist merely of a high resistance conductor.

40 I claim:
45 1. A high frequency producing means comprising a source of oscillations and means for multiplying the frequency of said oscillations including, a thermionic discharge device having input and output electrodes including a heated cathode, a transformer having its primary winding connected to said oscillator and its secondary winding connected in series with the heated cathode of said tube, an input circuit including an inductance 50 connected between the control electrode of said tube and the electrical midpoint of said secondary winding of said transformer, a second inductance connected with said oscillator and coupled to said first named inductance, a circuit connected between the output electrodes of said tube, and means in said output circuit for tuning the same to a multiple of the frequency of said source.

55 60 65 2. An arrangement as claimed in claim

1 in which a frequency multiplier is interposed between said source of oscillations and said inductance coupled to the input inductance.

3. An arrangement as claimed in claim 1 70 in which the cathode of said tube is of a high impedance.

4. An arrangement as claimed in claim 1 75 in which the thermionic tube is of the mercury vapor type provided with a heated cathode.
